UNITED STATES PATENT OFFICE.

EMIL FILLMANN, OF CHICAGO, ILLINOIS.

MOLDING.

SPECIFICATION forming part of Letters Patent No. 320,644, dated June 23, 1885.

Application filed May 5, 1885. (No model.)

To all whom it may concern:

Be it known that I, EMIL FILLMANN, a citizen of the United States of America, residing at Chicago, in the county of Cook and State 5 of Illinois, have invented certain new and useful Improvements in Moldings, of which the following is a specification, reference being had therein to the accompanying drawing.

My invention relates to an improved ornamental molding.

The object of the invention is to cheapen the cost of certain styles of such moldings, and also to lessen the amount of labor necessary for such manufacture.

To the accomplishment of the above the invention consists in forming one part of the molding of suitable ornamentations formed of what is known to the trade as "metal-leaf," and in forming the other part of the molding of a 20 series of pearls made of silver leaf lacquered.

Reference will be made to the drawing, in which is represented, in perspective, a section of molding embodying my invention.

A represents the wooden base, and B the 25 metallized portion of the molding, such metal leaf being formed into suitable ornamentations, as may be desired.

The term metal leaf, as herein used, will be understood to be the term used by the trade to distinguish bronze compositions and other 30 such compositions from the gold and silver leaf.

C represents a series of pearls which form part of the ornamental molding, such pearls being formed or made of silver leaf lacquered. 35

It will be understood that I do not wish to claim the use of metal leaf in forming moldings; nor do I wish to claim the use of silver leaf in the manufacture of moldings or other ornaments, as each has been utilized before; 40 but

What I do claim is—

Burnished pearls made of silver leaf, lacquered, in combination with ornamented metallized moldings, as set forth. 45

In testimony whereof I affix my signature in presence of two witnesses.

EMIL FILLMANN.
